UNITED STATES PATENT OFFICE.

ROPER COLBERT SPRATLING, OF GOLD HILL, ALABAMA.

DESIGN FOR A CHURN.

SPECIFICATION forming part of Design No. 31,822, dated November 14, 1899.

Application filed October 20, 1899. Serial No. 734,265. Term of patent 14 years.

To all whom it may concern:

Be it known that I, ROPER COLBERT SPRATLING, a citizen of the United States, residing at Gold Hill, in the county of Lee and State 5 of Alabama, have invented and produced a new and original Design for a Churn, of which the following is a specification.

This invention relates to a new and original design for a churn; and the essential features 10 of the same reside in a body of substantially rectangular form having the corners inclined, together with opposite sides having a shape in part similar to the body, provided with fixed divergent members connected by segmental 15 devices extending in planes at right angles thereto.

In the drawings, Figure 1 is a perspective view of a churn embodying the features of 20 the design. Fig. 2 is a central vertical longitudinal section of the same.

Similar numerals of reference indicate corresponding parts in the views.

The numeral 1 designates a substantially rectangular body, having the opposite ends 25 2 straight in the main and in planes at right angles to the upper and lower sides of the said body, the corners 3 being beveled in opposite directions. The body also has opposite flat side plates 4, with the upper corners 5 cut off 30 at a bevel and the lower portions of the opposite ends and the lower edge in planes at right angles to each other. The plates 4 have opposite divergent members 6, with the extremi-

ties projecting above and below the upper and lower edges of said plates, and said members are in parallel relation in a transverse direction and as disposed on the opposite plates. The lower terminals of the members 6 are connected by segmental elements 7, having upper straight edges 8 in planes parallel with the lower edges of the plates 4, the lower edges of the said element being curved, as at 9. From one upper extremity of one member 6, through the opposite similar extremity of the member parallel therewith, a cylindrical 45 bar 10 extends and is located over the body 1, near the ends of the latter, in each instance. From an intermediate point of the one element 7 to a similar part of the opposite element a pair of parallel cylindrical bars 11 50 also extend. The inner portions 12 of the opposite parts of the top of the body 1 adjacent the cover-opening are each curved in the arc of a circle and merge into the horizontal under surface of said parts of the top. 55

What is claimed is—

The design for a churn, herein shown and described.

In testimony that I claim the foregoing as my own I have hereto affixed my signature in 60 the presence of two witnesses.

ROPER COLBERT SPRATLING.
